INVENTOR

Ralph W. Oliver,
By *General Diamond Crompton*,
Atty.

UNITED STATES PATENT OFFICE.

RALPH W. OLIVER, OF TOLEDO, OHIO.

POWDER BOX.

Application filed May 18, 1922. Serial No. 561,880.

To all whom it may concern:

Be it known that I, RALPH W. OLIVER, a citizen of the United States, and a resident of Toledo, in the county of Lucas and State 5 of Ohio, have made an Invention Appertaining to a Powder Box; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to toilet articles and particularly to a powder box adapted to contain or receive a powder puff and a quantity of powder.

The object of the invention is the provision of a powder box having a chamber in its bottom for containing powder and adapted, by pressure on the top wall of the chamber, to discharge a small amount of powder from the chamber onto the top 25 thereof to facilitate gathering the powder on a powder puff without exposing all of the powder. The box is also adapted to contain a powder puff above the chamber.

Further objects and advantages of the invention will be apparent from the following 30 detailed description of the invention.

While the invention in its broader aspect is capable of embodiment in numerous forms, a preferred embodiment thereof is 35 illustrated in the accompanying drawings, in which,—

Figure 1 is a top plan view of a box embodying the invention in closed position. Fig. 2 is a front view thereof with the box 40 cover open and a powder puff in place in the box. Fig. 3 is a top plan view of the box in open position with the powder puff removed. Fig. 4 is a central vertical section of the box with the cover in open position, and Fig. 5 is a top plan view of the 45 flexible false bottom which forms the top of the powder containing chamber of the box.

Referring to the drawings, 1 designates 50 the body or bottom portion and 2 the cover of a box embodying the invention, which members may be hinged together and are preferably, though not necessarily, circular in form. The box body 1 is provided there- 55 in with a removable diaphragm 3 of any suitable fairly stiff material of a flexible

nature, such for instance as celluloid, tin, cardboard or the like, and this diaphragm is adapted to fit into the body member and is spaced therefrom by any suitable edge 60 spacing means to form a false bottom therefor. In the present instance, such spacing means comprises a ring of feltlike material 4 which is glued or otherwise suitably fixed to the bottom of the box body 65 around the interior edge portion thereof and a similar ring 5 is secured to the under marginal edge portion of the diaphragm 3 in position to seat down on the ring 4. These rings, being of a yielding material, 70 readily accommodate themselves to each other or to the surfaces against which they press, and form a close joint to prevent the escape of powder around the edge of the member 3.

75 The diaphragm 3, which is of disc form, when used in connection with a circular form of box, is supported by the members 4 and 5 or other suitable spacing means above the bottom of the box body and cooperates therewith to form a chamber 6 in the bottom of the box body for containing 80 a quantity of powder and forms the bottom of an upper chamber. The diaphragm 3 is of a flexible nature to adapt it to be 85 pressed down into the chamber at its central portion, and is provided with one or more centrally disposed perforations 8 so that when depressed into engagement with the powder in the chamber 7 the air which 90 rushes out from the chamber through the perforations during the compressing action carries with it a greater or less quantity of powder which gathers on the top of the diaphragm 3 in segregating relation to the 95 powder in the chamber 7 and in position to be gathered up by the powder puff. It is found in practice that it is not necessary to completely compress the diaphragm 3 to 100 eject powder from the chamber 7 onto the top of the member, but that a few light taps of a finger on the diaphragm will cause a sufficient agitation of air within the chamber to eject a small quantity of powder therefrom.

105 By the use of my invention it is possible to use powder in powder puff boxes without danger of spilling the powder and obviates the use of powder cakes in such boxes. The diaphragm or false bottom 3 has a sufficiently snug fit in the box to prevent its falling therefrom should the box be invert-

ed and a removal of the diaphragm from the box is facilitated by a tab 9 on one edge thereof.

I wish it understood that my invention is not limited to any specific construction, arrangement or form of the parts, as it is capable of embodiment in numerous forms without departing from the spirit of the claims.

10 Having thus described my invention, what I claim as new, and desire to secure by Letters Patent, is,—

1. In a box of the class described, a flexible diaphragm removable therefrom and having centrally disposed perforations, a ring of felt-like material spacing the marginal edge portion of the diaphragm from the box bottom and compressible by pressure on the diaphragm to form a close joint

20 between the diaphragm and bottom, the diaphragm, box bottom and ring cooperating to form a powder receiving chamber.

2. A powder box having horizontally connected top and body portions, a flexible diaphragm removably mounted in the body portion of the box and having centrally disposed perforations, separate marginal ring-like members of a soft compressible material secured to the box bottom and diaphragm respectively in position to seat one against the other to space the diaphragm from the box bottom and to co-operate therewith to form a powder chamber which is closed except for the perforations in the diaphragm.

25 In testimony whereof, I have hereunto signed my name to this specification.

30 RALPH W. OLIVER.
